UNITED STATES PATENT OFFICE.

ANGEL PONS, OF BUFFALO, NEW YORK.

FIBER-CLEANING MACHINE.

No. 899,070.

Specification of Letters Patent.

Patented Sept. 22, 1908.

Application filed November 22, 1905. Serial No. 288,523.

To all whom it may concern:

Be it known that I, ANGEL PONS, a subject of the King of Spain, residing in the city of Buffalo, county of Erie, State of New York, have invented certain new and useful Improvements in Fiber-Cleaning Machines, of which the following is a specification, reference being had therein to the accompanying drawings, in which—

10 Figure 1 is a side elevation of the machine in position for operating. Fig. 2 a side elevation from the opposite side showing the machine in position for transportation; Fig. 3 a front elevation thereof; Fig. 4 a rear elevation; Fig. 5 a longitudinal vertical sectional view; Fig. 6 a detail view of the means for securing the knives to the cleaning drum; Fig. 7 a detail sectional view of one of the presser plates; and Fig. 8 a detail view of the 20 adjustable bearing of the cleaning drum shafts.

One of the many objects of this invention is to produce a machine especially adapted to strip the fiber from long leaves, such as the 25 abaca (Manila hemp) planato (banana) pita, etc., and wherein the leaf will be fed into the machine longitudinally and will be scraped from end to end.

Another object of the invention is to provide a machine wherein the leaves will be given an initial scraping and then a final scraping so that the fiber is very clean when it is delivered from the machine.

A further object of the invention is to provide means whereby the leaf will be almost entirely fed through the machine in one direction and partially or initially scraped, and will then be drawn back by the same feeding means, the same scraping means serving as a 40 final scraping means when the direction of movement of the leaf is changed.

It is also the object of this invention to provide means whereby the leaf when it is first inserted in the machine will cause the 45 feeding means to rotate in the proper direction to feed the leaf to the cleaning drum, and whereby said leaf after a certain portion of it has been cleaned will permit the automatic reversal of the feeding means, whereby 50 the direction of movement of the leaf will be changed without changing the direction of movement of the cleaning drum.

These are some of the most important objects of the invention. Other equally important objects and advantages of the invention will appear hereinafter.

Referring to the various parts by numerals, 1 designates the framing of the machine, in the upper rear end of which is mounted a transverse horizontal driving shaft 2. On 60 this shaft outside of the supporting frame and near each end thereof is adjustably secured a large fly-wheel 3. These wheels are provided with cranks 4 by means of which they may be rotated and the machine operated when said wheels are made fast to the shaft 2 by set screws 4^a. Mounted on this shaft is a large sprocket wheel 5 over which runs a sprocket chain 6. This sprocket chain engages the sprocket wheel 7 rigidly 65 secured to a transverse drum carrying shaft 8. A drum 9 is rigidly mounted on said shaft between the side pieces of the supporting frame, and projecting radially from the surface of said drum are the cleaning knives 10, said knives being suitably secured to said drum and projecting beyond the periphery thereof, as clearly shown in the drawings. Mounted in the frame forward of the cleaning drum 9 are two transverse parallel shafts 80 11 which are located suitable distances apart and have rigidly secured to them between the side frames of the machine two feeding rolls 12. These rolls are formed with transverse parallel ribs and depressions, the rolls 85 being so adjusted with respect to each other that the ribs of one roll engage the corresponding corrugations of the other roll; so that when said rolls are rotated they will grip the leaves between them and form a 90 positive feeding means, in contradistinction to the feeding rolls which operate merely by friction. Loosely mounted on each shaft 11 is a sprocket wheel 13 which carries one member of a clutch 14, the other member thereof being adapted to be brought into engagement therewith by means which will be hereinafter described, said sprocket wheel being caused to run fast or loose on the shafts 11 by 95 said clutches.

In the forward upper end of the machine is mounted a pair of transverse horizontal smooth receiving rolls 15, the lower one of which is mounted on a shaft 16 journaled in rigid bearings. The upper roll is carried by 105 a shaft 17 which is journaled in blocks yieldably mounted in boxes 18 formed in the sides of the machine frame. In these boxes are arranged coil springs 19 which bear upon the journal blocks and normally hold them at 110 the bottom of the boxes 18, the two feeding rolls in this position of the box engaging each

other as shown clearly in Fig. 3. It will thus be seen that the upper feeding roll is yieldably held in engagement with the lower feeding roll. The shafts of these two rolls are 5 geared together by means of the gears 20 and 21, the teeth of said gears being large enough to permit the upper receiving roll to have a slight outward movement without disengaging said teeth. One end of the shaft 17, the 10 right hand end as shown in Fig. 3, is provided with a depending arm 22 which is loosely connected by means of a pin 23 to a downwardly and rearwardly extending rock shaft 24 which is mounted in bearings on the outer 15 side of the machine frame. On this rock shaft near the rear or inner end thereof is rigidly secured a bar 25, the upper and lower ends of which are formed into yokes 26 which are adapted to engage the movable members 20 of the clutches 14, said members being secured to the shafts 11 with the usual spline and groove. The sprocket wheels 13 are driven by a chain 27 from the drum shaft 8, and when the upper receiving roll 15 is in 25 contact with the lower receiving roll the members of the lower clutch 14 are in engagement as shown in Fig. 3, and the lower corrugated roll 12 is driven by the chain 27 while the upper sprocket 13 runs loosely on 30 its shaft. When a leaf is inserted between the two receiving rolls 15, the upper roll is forced upward against the springs 19, causing the arm 22 to rock shaft 24 and thereby throw out the lower clutch and bring the 35 members of the upper clutch into engagement whereby the chain 27 will drive the upper sprocket wheel 13, the lower sprocket wheel running loosely on its shaft. This movement of the clutches reverses the direction 40 of rotation of the corrugated feeding rolls, as will be more fully hereinafter described.

The shaft of the upper corrugated feeding roll is mounted in suitable journal boxes 45 which are yieldably held in position by means of springs 28 whereby said roll may yield or move outward slightly to receive the leaves. Below the lower receiving roll 15 and at the forward end of the machine is 50 mounted a transverse horizontal roller 29 which is arranged close to and parallel with said roll. Over this roller is arranged a feed belt 30 which passes around the lower corrugated feed rolls 12 and receives its motion 55 therefrom, the direction of movement of said belt being reversed when the direction of rotation of the feeding roll is reversed. The shafts of the feeding rolls 12 are geared together by gears 31, as shown in Fig. 2, so 60 that said rolls are positively driven one from the other. The chain 27 passes over the small sprocket wheel 32 mounted on the transverse shaft 33, and on the opposite end of said shaft is secured a sprocket wheel 34 65 over which runs a sprocket chain 35, said

chain driving a sprocket wheel 36 mounted on the shaft of the lower receiving roll 15. The receiving rolls rotate in one direction at all times during the operation of the machine.

In the lower part of the frame of the machine forward of the first cleaning wheel and below the same, is mounted a transverse shaft 37 on which is mounted a second cleaning drum 38, said drum carrying in its periphery cleaning knives 39. On one end of the shaft 37 is secured a sprocket wheel 40 over which runs the chain 27, said sprocket wheel and the corresponding sprocket wheel on the shaft of the first cleaning drum being of the same size, the chain being arranged to run thereon in such manner as to drive both cleaning drums in the same direction. In the frame forward of the second cleaning drum and slightly above it are mounted two longitudinally corrugated feeding rolls 41, the shaft 42 of the upper roll being journaled in boxes 43 which are yieldingly held in position by springs 44. The shafts of these rolls are connected together by means of gears 45, and on the shaft of one of said rolls is secured a sprocket wheel 46 over which runs a sprocket chain 47 said chain being driven by a small sprocket wheel 48 mounted on a transverse shaft 49. On this shaft is secured a large gear 50 which meshes with the gear 31 secured to the lower transverse shaft 11 of the upper set of corrugated feeding rolls. The lower feeding roll 41 is much larger in diameter than its co-acting roll so that when the end of the leaf is delivered to said rolls by the belt 30 said end will be caught by the larger lower roll and carried inward to the other roll, as will be hereinafter described. The sprocket wheels driving the rolls 41 are so proportioned that said second set will have one-fourth the speed of the first set of rolls 12, for purposes which will hereinafter be fully described.

Forward of the first cleaning wheel and in position to receive the end of the leaf from the first set of positive feed rolls 12 is arranged a curved presser plate 51 which is substantially concentric to the cleaning drum. The upper end of this presser plate is arranged so that the end of the leaf on emerging from the feed rolls 12 will be received between said plate and the cleaning drum, and will then be carried by the cleaning knives along said plate, said knives scraping the leaf as it passes through the channel between the plate and the drum. The upper end of this plate is pivotally mounted upon end studs 52 and its lower end is adjustably supported by screws 53. By means of the screws the presser plate may be so adjusted as to secure the proper operation of the knives on the leaves.

The presser plate 54 is arranged forward of the second cleaning wheel and is adapted to

receive the leaf from the second set of positive feeding rolls 41; and this presser plate is provided with adjusting screws 55, its upper end being pivotally mounted upon end studs 56. At the forward end of the belt 30 is arranged a depending guide plate 57 which receives the leaf from said belt and directs it to the feed rolls 41, a screw 58 being provided by which this guide plate may be adjusted to 10 deliver the leaf at the proper point on the lower larger feed roll 41.

The shafts of the cleaning drums are mounted in movable journal boxes 59 which are adapted to be adjusted by means of 15 screws 60 to secure the proper relative positions of the cleaning knives and the presser plates. The cleaning knives are adjustably secured in the cleaning drums. By reference to Fig. 6 it will be seen that the knives 20 are formed with threaded extensions 61 by means of which they may be readily adjusted in the drum. The drums are each formed with inwardly extending transverse enlargements 62 which are transversely channeled 25 to receive the knives. Arranged to bear against one side of each of the knives is a transverse wedge bar 63, one face of which extends inward and away from the knife. Engaging this inclined face of the wedge bar 30 is a correspondingly inclined face of a bolt head 64, said bolt extending through the enlargement 61 and being securely locked in place by a nut 65. It will be readily seen that by clamping the bolt in place the wedge bar 35 is forced against the knife and the knife readily clamped in the channel formed in the cleaning drum. It will be noted that the head of the bolt and the wedge bar are below the periphery of the drum.

40 The presser plates are formed with side flanges 66 as shown clearly in Fig. 7 to prevent the fiber, or any portion of the leaf, escaping from said plates at the sides thereof.

The machine at its forward end is supported 45 on small transporting wheels 67 which are secured on a transverse shaft 68 suitably mounted in the frame. When the machine is in its operative position it is supported at its rear end on legs 69 which are pivoted at 50 70 on the frame, and incline rearwardly. These legs are formed with extensions 71 which extend above the pivots and rest against flanges 72 formed on the frame. In this position the weight of the rear part of 55 the machine is sustained by the legs. When it is desired to transport the machine from place to place the legs are swung forward on the pivots 70 and held up out of operating position by means of a hook 73 as shown in 60 Fig. 2. This permits the machine to be lowered until the large fly-wheels rest upon the ground and support the machine. These wheels are then permitted to run loose on the driving shaft by loosening the set screws 4^a; 65 When in this position the machine may be

readily moved from place to place, the fly-wheels and wheels 66 at the forward end of the machine, serving as transporting wheels.

The operation of the machine is as follows:—One end of the leaf, preferably the 70 thinner end, is introduced between the smooth receiving rolls, forcing upward the upper roll, thereby through the arm 22 and the rock shaft 24, throwing the upper clutch yoke 26 inward and bringing into engagement the members of the clutch 14 connected to the upper sprocket wheel 13. The driving shaft is rotated in the direction indicated by the arrow in Fig. 1 so that the upper sprocket wheel and the connected receiving rolls are 80 driven in the proper direction to draw the leaf inward. As the belt 30 is driven by the lower corrugated feed roll 12 it will also move to carry the leaf inward toward the first or primary cleaning drum. As the leaf is 85 drawn inward by the smooth feed rolls, it drops down to the belt 30 and by it is carried inward to the positive feed rolls 12. By these latter rolls the leaf is positively fed inward into the channel, between the presser 90 plate 51 and the first cleaning drum 9. This cleaning drum rotates at a constant speed and in the direction indicated by the arrow and scrapes the pulpy matter from the leaf, leaving the fiber uninjured and also carrying 95 the fibers through the channel formed by the presser plate, and causing the clean leaf to emerge from said channel at the rear end of said plate. The knives in the cleaning drum and the presser plate are so adjusted that the 100 fibers are left comparatively clean after the first scraping or cleaning operation. When the butt end of the leaf has passed between the receiving rolls and dropped to the belt 30, the upper receiving roll will be moved 105 inward by the springs 19 and the rock shaft 24 will be moved through its connection with the shaft of said roll to disengage the members of the upper clutch and to throw into engagement the members of the lower clutch. 110 This will cause the lower sprocket wheel 13 to rotate with its shaft and the upper one to run loosely, thereby reversing the motion of the positive feed rolls and the belt 30. It will be noted that this reversal of the motion 115 of these parts will take place before the butt end of the leaf has passed between the positive feed rolls. The result of this is that the direction of movement of the leaf will be reversed and that the positive feed rolls will 120 draw the clean leaf back through the channel between the presser-plate 51 and the first cleaning drum, and that as said cleaning drum continues its rotation that portion of the leaf will be again scraped, so that the 125 fibers after they have passed the second time through said cleaning channel will be thoroughly cleaned. The belt 30 will deliver the unscraped end of the leaf against the plate 57 by which it will be directed downward and 130

slightly rearward to the second set of positive feed rolls 41. The larger of these rolls will first engage the leaf and direct it rearward and between the rolls. These corrugated gripping rolls will receive the leaf and draw it forward and deliver it into the channel between the second presser plate and the second cleaning wheel, the action of the said cleaning wheel and presser plate being exactly the same as the first cleaning wheel and its presser plate. These second positive feed rolls, it will be remembered, are moved at one-fourth the speed of the first positive feed rolls so that a greater portion of the leaf will be delivered to the belt 30 and by the belt 30 to the feed rolls 41, than will be fed by these latter rolls to the second cleaning drum. The result of this will be that the entire leaf will be discharged over the forward end of said belt 30 when only about one-fourth of it has been fed by the second positive feed rolls to the second cleaning drum, the surplus leaf falling down in front of the machine. It is obvious that the roll 41 of the second feed rolls will not support the surplus leaf that is delivered to it by the belt 30, and that that portion of it which is not fed to the second cleaning means will naturally drop down in front of the machine. The purpose of this is to have the second cleaning drum act only upon that part of the leaf that was not acted upon by the first cleaning drum, or approximately so. As soon as the cleaned end of the leaf has dropped from the belt 30 the thinner end of another leaf is inserted between the receiving rolls 15 thereby forcing upward the upper roll and again reversing the direction of rotation of the feed rolls and belt 30, so that the new leaf will be carried inward to the positive feed rolls 12 and be delivered to the first cleaning drum. It will be noted that this action will also reverse the direction of rotation of the second set of positive feed rolls 41 and that instead of feeding the leaf to the second cleaning drum they will act to draw the portion so fed, back through the cleaning channel, said portion being a second time scraped. It will therefore, be seen that when the leaf or strick of fiber is finally delivered at the front of the machine it has been scraped twice throughout its entire length, without any handling by the operator except to insert one end thereof between the receiving rolls, all subsequent operations being automatic. It will also be noted that the new leaf may be inserted between the receiving rolls before the first leaf has passed entirely through the machine so that a considerable saving of time is effected.

While I have described what I now consider a preferred form of my invention, it is manifest that many changes and modifications may be made therein, and I desire it understood that I do not wish to be limited to the exact form of machine shown, but de-

sire it understood that said machine is merely illustrated. I desire it also understood that while I describe the machine in detail, I do not wish to be understood as limiting myself to the exact arrangement or construction of the parts as shown and described, except, in so far as I may be restricted by the claims.

Having thus described my invention, what I claim as new and desire to secure by Letters Patent, is:—

1. A fiber cleaning machine comprising a leaf cleaning means, a feed mechanism for feeding the leaf to the cleaning means, and means to be moved by the leaf for reversing the direction of movement of the feeding means, whereby the leaf may first be fed into the cleaning mechanism and may then be drawn back through said cleaning means in the reverse direction.

2. A fiber cleaning machine comprising a cleaning mechanism, a positive feed mechanism adapted to deliver the leaf to the cleaning means, and means to be moved by the leaf for automatically reversing the direction of movement of the feeding means to draw the leaf back through the cleaning mechanism.

3. A fiber cleaning machine comprising a rotary cleaning means, means for giving said cleaning means a constant movement in one direction, a positive feeding means, means for operating the feeding means, and means to be moved by the leaf for reversing the direction of movement of the feeding means without reversing the movement of the cleaning device, whereby the leaf may be passed through the cleaning means and drawn back therefrom by the feeding means during the rotation of the cleaning device in one direction.

4. A fiber cleaning machine comprising a rotary cleaning means, rotary longitudinally corrugated positive feed rolls adapted to intermesh, means for rotating the cleaning means and the feed rolls, and means to be moved by the leaf for reversing the direction of rotation of the feed rolls without reversing the movement of the cleaning device, whereby the leaf may be fed to the cleaning means in one direction and drawn back through said cleaning means in the opposite direction during the rotation of the cleaning means.

5. A fiber cleaning machine comprising a pair of receiving rolls, a pair of positive feed rolls to take the leaf from the receiving rolls, a cleaning device adapted to receive the leaf from the positive feed rolls, and means controlled by the entrance of one end of the leaf to be treated between the receiving rolls and the exit of said leaf from said receiving rolls for reversing the direction of the rotation of the positive feed rolls, whereby the leaf may be fed almost entirely to the cleaning means in one direction and may then be drawn back

through said cleaning means, whereby the cleaning device will operate for a second time on the leaf.

6. A fiber cleaning machine comprising a cleaning means, a feed mechanism adapted to feed the leaf lengthwise into the cleaning means and to draw it back through said cleaning means after the greater portion of the length of said leaf has entered said cleaning means, and means to be moved by the leaf for reversing the feed mechanism.

7. A fiber cleaning machine comprising cleaning means, positive feed rolls adapted to feed the leaf to the cleaning means, receiving rolls to receive the leaf and deliver it to the positive feed rolls, and means actuated by the insertion of one end of the leaf between the feed rolls to reverse the direction of the rotation of the positive feed rolls, whereby when the other end of the leaf has passed between the feeding rolls means will be actuated to reverse the direction of the positive feed rolls.

8. A fiber cleaning machine comprising a cleaning means, a pair of rotatable positive feed rolls, receiving rolls adapted to receive the leaf and to deliver it to the positive feed rolls, one of said receiving rolls being movable, and means actuated by the movement of said movable roll to reverse the direction of rotation of the positive feed rolls.

9. A fiber cleaning machine comprising a cleaning means, a pair of positive feed rolls adapted to deliver the leaf to the cleaning means, a pair of receiving rolls, one of said rolls being movable away from the other, and means operated by the movement of said roll to reverse the direction of rotation of the positive feed rolls, a belt to receive the leaf from the receiving rolls and to deliver it to the positive feed rolls, the direction of movement of said belt being reversed when the positive feed rolls are reversed.

10. A fiber cleaning machine comprising a cleaning means, a feed device for feeding the leaf to said cleaning means, means to be moved by the leaf for changing the direction of rotation of said feeding means, a second cleaning means, a feed device to deliver the leaf from the first feed device to the second cleaning means, and means whereby the feed devices for the two cleaning means will move in opposite directions.

11. A fiber cleaning machine comprising a primary cleaning means, feed mechanism to feed the leaf longitudinally into said cleaning mechanism, means controlled by the movement of the leaf into the machine for reversing the movement of said feeding means, a secondary cleaning means, means for feeding the leaf to said secondary means, said feeding means being adapted to receive the leaf from the primary feeding means, whereby the leaf will be drawn back through the primary cleaning means and delivered to the

feeding means of the secondary cleaning means, and means whereby the two feeding means will move in opposite directions, whereby when the first feeding means is moving in the direction to deliver the leaf into the first cleaning means the second feeding means will be moving in the direction to withdraw the leaf from the second cleaning means.

12. A fiber cleaning machine comprising two cleaning devices, feeding means for feeding the leaf to each cleaning device, means to be moved by the leaf for reversing the motion of the feeding means, and means whereby one cleaning device will be receiving the leaf when it is being drawn away from the other cleaning means so that the cleaning means will operate upon the leaf in succession.

13. A fiber cleaning machine comprising two cleaning drums, a feed device for each drum, means for operating said feed devices at different speeds, means for reversing the movement of the feeding means without reversing the motion of the cleaning drums.

14. A fiber cleaning machine comprising a pair of cleaning drums, a primary feeding means to feed the leaf to be cleaned end first to one of said cleaning drums, means controlled by the passage of the leaf into the machine for reversing the direction of movement of the primary feeding means when a certain length of the leaf has been acted upon by the primary feeding means, whereby said primary feeding means will then serve to draw the leaf back from the cleaning drum, a secondary feeding means adapted to receive the leaf from the primary feeding means and to deliver it to the second cleaning drum, means connecting the primary feeding means to the secondary feeding means to cause the two feeding means to rotate in opposite directions, and means for rotating the cleaning drums in the same direction at all times.

15. A fiber cleaning machine comprising a pair of receiving rolls, means for yieldably mounting one of said rolls, a pair of feed rolls to take the leaf from the receiving rolls, a cleaning drum to receive the leaf from the feed roll, means operated by the movable receiving roll when the leaf is inserted between the receiving rolls to cause the feed rolls to move in the proper direction to feed the leaf to the cleaning drum, and means operated by the movable roll of the receiving rolls when the said roll is returned to its normal position after the leaf has passed entirely through said rolls to reverse the direction of rotation of the feed rolls to draw the leaf back from the cleaning drum during the rotation of said drum.

16. A fiber cleaning machine comprising a primary cleaning means, a primary feeding means, means for reversing the movement of the primary feeding means before the

entire leaf has passed to the primary cleaning means, whereby the leaf will be drawn back from the primary feeding means, a secondary cleaning means, a secondary feeding means to feed the leaf to said secondary cleaning means and means whereby the leaf will be delivered to the secondary feeding means from the primary feeding means, and means for reversing the direction of movement of the secondary feeding means before the entire leaf has been delivered to the secondary cleaning means, and means for driving the secondary feeding means at a less speed than the primary feeding means, whereby a smaller portion of the leaf will be fed to the secondary cleaning means than to the primary cleaning means.

17. A fiber cleaning machine comprising a cleaning drum, a pair of positive feed rolls, a pair of receiving rolls, a delivery belt adapted to carry the end of the leaf from the receiving rolls to the feed rolls, a rock-shaft means actuated by the insertion of the leaf to be treated between the receiving rolls for partially rotating said rock-shaft and means operated by the partial rotation of said rock-shaft to change the direction of rotation of the feeding means and of the feed belt.

18. A fiber cleaning machine comprising a cleaning drum, means for feeding the leaf, end first, to said cleaning drum and in the direction of the rotation of said drum, means for reversing the movement of the feeding means to draw the leaf from said cleaning drum in the reverse direction, whereby the portion of the leaf operated upon will be scraped a second time, a second cleaning drum, a feeding means for delivering the leaf with its other end first to said cleaning drum, means for moving said second feeding means at a less speed than the first feeding means, whereby the greater portion of the leaf will be cleaned by the first cleaning drum, and means for reversing the direction of movement of the second feeding means.

19. A fiber cleaning machine comprising a cleaning drum, means for feeding the leaf, end first, to said drum in the direction of rotation of said drum, means for reversing the movement of the feeding means to be moved by the leaf to draw the leaf from said cleaning drum without reversing the direction of rotation of the drum, whereby that portion of the leaf fed to the drum will be scraped twice.

20. A fiber cleaning machine comprising a pair of receiving rolls, means for yieldably maintaining one of said rolls in contact with the other receiving roll, a pair of corrugated feed rolls to take the leaf from the receiving rolls, a sprocket wheel loosely mounted on the shaft of each of said positive feed rolls, a clutch mechanism operated by the movably mounted receiving roll to alternately connect said sprocket wheels to the shafts of the

positive feed rolls, a cleaning drum, a sprocket wheel on the shaft of said drum, a sprocket chain engaging the sprockets on the shafts of the positive feed rolls and on the cleaning drum shaft, a driving shaft, and means connecting the driving shaft with the shaft of the cleaning drum.

21. A fiber cleaning machine comprising a pair of receiving rolls, means for yieldably maintaining one of said rolls in contact with the other receiving roll, a pair of corrugated feed rolls to take the leaf from the receiving rolls, a sprocket wheel loosely mounted on the shaft of each of said positive feed rolls, a clutch mechanism, a rock-shaft connected thereto, means operated by the movably mounted receiving roll to move the rock-shaft to alternately connect said sprocket wheels to the shafts of the positive feed rolls, a cleaning drum, a sprocket wheel on the shaft of said drum, a sprocket chain engaging the sprockets on the shafts of the positive feed rolls and on the cleaning drum shaft, a driving shaft, and means connecting the driving shaft with the shaft of the cleaning drum.

22. A fiber cleaning machine comprising two cleaning drums, means for rotating said drums in the same direction, and at the same speed, two feeding means, means for rotating said feeding means at different speeds, means for delivering the leaf, end first, to the feeding means having the greater speed, and means for reversing the movement of said feeding means to deliver the leaf with its other end first to the slower moving feeding means, and means for reversing the movement of this second feeding means.

23. A scraping drum for fiber cleaning machines provided with a transverse channel, a knife adapted to fit therein and project slightly beyond the periphery of the drum, a wedge key adapted to bear against one side of said knife, and a clamping bolt extending to the interior of the drum and provided with a head adapted to bear against the wedge key and force the same against the knife to clamp the knife against one wall of the channel.

24. A fiber cleaning machine comprising two cleaning drums, means for rotating said drums in the same direction, two feeding means, one for each drum, means for rotating said feeding means at different speeds, means for delivering the leaf one end first to the feeding means having the greater speed, means for reversing the movement of said feeding means to deliver the leaf with its other end first to the slower moving feeding means.

25. A fiber cleaning machine comprising two cleaning drums, means for rotating said drums in the same direction, two feeding means, one for each drum, means for rotating said feeding means in opposite directions, a

leaf-receiving means adapted to receive the leaf and deliver it to the first feeding means, means for moving said receiving means constantly in one direction, means for reversing the direction of rotation of the feeding means without reversing the direction of movement of the receiving means, the two feeding means being so arranged that when moving in one direction one of said feeding means 10 will deliver to the other.

26. A fiber cleaning machine comprising a cleaning drum, feed rolls, receiving rolls, one of said receiving rolls being movable away from the other roll, means for rotating 15 said receiving rolls constantly in one direction, and means operated by the movement of the movable feed roll to reverse the direction of rotation of the feed rolls.

27. A fiber cleaning machine comprising 20 a supporting frame, a primary cleaning drum mounted in said frame in the upper rear end thereof, a pair of primary feed rolls forward of said cleaning drum, a curved presser plate for said primary cleaning drum near the forward side thereof, a feed belt adapted to deliver the leaf to the primary feed rolls, a secondary cleaning drum forward and below the primary cleaning drum, a presser plate for said secondary cleaning drum mounted 25 near the forward side thereof, a pair of secondary feed rolls for said secondary cleaning drum, said secondary feed rolls being located below the forward end of the feed belt, means whereby the primary feed rolls and the 30 secondary feed rolls will be rotated in opposite directions, means for simultaneously reversing the direction of rotation of the feed rolls, and means for rotating the cleaning drums in one direction and so that the cleaning knives carried thereby will move down 35 the presser plate toward the rear of the machine.

28. A fiber cleaning machine comprising a supporting frame, a primary cleaning drum 40 mounted in said frame in the upper rear end thereof, a pair of primary feed rolls forward of said cleaning drum, a curved presser plate for said primary cleaning drum near the forward side thereof, a feed belt adapted to deliver the leaf to the primary feed rolls, a secondary cleaning drum forward and below the primary cleaning drum, a presser plate for 45 said secondary cleaning drum mounted near the forward side thereof, a pair of secondary feed rolls for said secondary cleaning drum, said secondary feed rolls being located below the forward end of the feed belt, means whereby the primary feed rolls and the secondary feed rolls will be rotated in opposite 50 directions, means for reversing the direction of rotation of the feed rolls, and means for rotating the cleaning drums in the same direction and the secondary feed rolls will be rotated at a slower speed than the primary feed rolls, means for reversing the direction 55 of rotation of the feed rolls, and means for rotating the cleaning drums in the same direction.

29. A fiber cleaning machine comprising a supporting frame, a primary cleaning drum mounted in said frame in the upper rear end thereof, a pair of primary feed rolls forward of said cleaning drum, a curved presser plate for 50 said primary cleaning drum near the forward side thereof, a feed belt adapted to deliver the leaf to the primary feed rolls, a secondary cleaning drum forward and below the primary cleaning drum, a presser plate for 55 said secondary cleaning drum mounted near the forward side thereof, a pair of secondary feed rolls for said secondary cleaning drum, said secondary feed rolls being located below the forward end of the feed belt, means whereby the primary feed rolls and the secondary feed rolls will be rotated in opposite directions, means for reversing the direction of rotation of the feed rolls, means for 60 rotating the cleaning drums in the same direction, a driving shaft in the frame above the primary cleaning drum, means connecting said driving shaft with the operating mechanism, a pair of fly-wheels on said driving shaft, means for connecting and disconnecting said fly-wheels to said shaft, and adjustable means for supporting the forward end of the machine whereby the fly-wheels may be held clear of the ground or be 65 permitted to rest thereon to serve as trans- 70 porting wheels.

30. A fiber cleaning machine comprising a supporting frame, a primary cleaning drum mounted in said frame in the upper rear end thereof, a pair of primary feed rolls forward 75 of said cleaning drum, a curved presser plate for said primary cleaning drum near the forward side thereof, a feed belt adapted to deliver the leaf to the primary feed rolls, a secondary cleaning drum forward and below the primary cleaning drum, a presser plate for 80 said secondary cleaning drum mounted near the forward side thereof, a pair of secondary feed rolls for said secondary cleaning drum, said secondary feed rolls being located below the forward end of the feed belt, means whereby the primary feed rolls and the secondary feed rolls will be rotated in opposite 85 directions, means for reversing the direction of rotation of the feed rolls, means for rotating the cleaning drums in one direction, a pair of receiving rolls above the forward end of the feed belt and adapted to deliver the leaf to be cleaned to said belt, and means for 90 rotating said receiving rolls constantly in one direction.

31. A fiber cleaning machine comprising a supporting frame, a primary cleaning drum mounted in said frame in the upper rear end thereof, a pair of primary feed rolls forward 95 of said drum, a curved presser plate for said primary cleaning drum near the forward side thereof, a feed belt adapted to deliver the leaf to the primary feed rolls, a secondary cleaning drum forward and below the pri- 100

mary cleaning drum, a presser plate for said secondary cleaning drum mounted near the forward side thereof, a pair of secondary feed rolls for said secondary cleaning drum, 5 said secondary feed rolls being located below the forward end of the feed belt, means whereby the primary feed rolls and the secondary feed rolls will be rotated in opposite directions and the secondary feed rolls will 10 be rotated at a slower speed than the primary feed rolls, means for rotating the cleaning drums in one direction, a deflector plate at the forward end of the feed belt and adapted to direct the leaf to be cleaned to the secondary feed rolls.

32. A fiber cleaning machine comprising a supporting frame, a primary cleaning drum mounted in said frame in the upper rear end thereof, a pair of primary feed rolls forward 20 of said cleaning drum, a curved presser plate for said primary cleaning drum near the forward side thereof, a feed belt adapted to deliver the leaf to the primary feed rolls, a secondary cleaning drum forward and below 25 the primary cleaning drum, a presser plate for said secondary cleaning drum mounted near the forward side thereof, a pair of feed rolls for said secondary cleaning drum, said secondary feed rolls being located below the forward end of the feed belt, means whereby the primary feed rolls and the secondary feed rolls will be rotated in opposite directions, means for reversing the direction of rotation 30 of the feed rolls, means for rotating the cleaning drums in one direction, a pair of receiving rolls above the forward end of the feed belt and adapted to deliver the leaf to be cleaned to said belt, one of said rolls being laterally movable, means for rotating said receiving 35 rolls constantly in one direction, and means operated by the lateral movement of one receiving roll in one direction to cause the feed rolls to rotate in one direction and by the return of said receiving roll to its normal 40 position to reverse the direction of rotation of the feed rolls.

33. A fiber cleaning machine comprising a pair of receiving rolls, means for rotating said receiving rolls in one direction, means for 50 yieldably maintaining one of said rolls in contact with the other receiving roll, a pair of feed rolls to take the leaf from the receiving rolls, a clutch mechanism operated by the movably-mounted receiving roll to alternately 55 connect the shafts of the feed rolls to the operating mechanism whereby said shafts may be rotated first in one direction and then in the reverse direction, a cleaning drum, and means for rotating said drum and 60 the shafts of the feed rolls.

34. A fiber cleaning machine comprising a pair of receiving rolls, means for rotating said receiving rolls constantly in one direction, means for yieldably maintaining one of said 65 rolls in contact with the other receiving rolls,

a pair of feed rolls to take the leaf from the receiving rolls, a clutch mechanism adapted to alternately connect the shafts of the feed rolls to their operating mechanisms whereby said feed rolls may be first rotated in one 70 direction and then in the reverse direction, a rock shaft connected to said clutch mechanism and to the movably mounted receiving roll, whereby said clutch mechanism may be operated through the movable receiving roll, 75 a cleaning drum, and means for rotating said cleaning drum and the shafts of the feed rolls.

35. A fiber cleaning machine comprising two cleaning drums, two feed devices, one 80 for each drum, means for rotating the drums in the same direction, means for rotating the feed devices in opposite directions, so that when one feeding device is delivering a leaf to its cleaning drum, the other feeding device 85 will be withdrawing a leaf from its feeding drum, and means for reversing the direction of rotation of the feeding devices.

36. A fiber cleaning machine comprising two cleaning drums, means for rotating said 90 drums, two feeding means one for each drum, means for rotating said feeding means in opposite directions and at different speeds.

37. A fiber cleaning machine comprising two cleaning drums, means for rotating said 95 drums, two feeding means one for each drum, means for rotating said feeding means in opposite directions and at different speeds, and means for reversing the feeding means.

38. A fiber cleaning machine comprising a 100 primary feeding means, a primary cleaning wheel, a secondary feeding means below the primary feeding means, a secondary cleaning wheel below the primary cleaning wheel, means for rotating the feeding means in opposite direction, means for delivering the leaf to be cleaned from the primary feeding means to the secondary feeding means, and means for reversing the secondary feeding means to withdraw the cleaned fiber from the 110 secondary cleaning means.

39. A fiber cleaning machine comprising a primary feeding means, a primary cleaning wheel, a secondary feeding means below the primary feeding means, a secondary cleaning 115 wheel below the primary cleaning wheel, means for rotating the feeding means in opposite direction, means for delivering the leaf to be cleaned from the primary feeding means to the secondary feeding means, and means for reversing the secondary feeding means to withdraw the cleaned fiber from the 120 secondary cleaning means, and means for rotating the secondary feeding means at a slower speed than the primary feeding 125 means.

40. A fiber cleaning machine comprising a primary feeding means, a cleaning drum adjacent thereto, a secondary feeding means, a 130 cleaning drum therefor, means whereby when

- the primary feeding means is reversed the leaf to be cleaned will be delivered to the secondary feeding means, said secondary feeding means being arranged to discharge the cleaned fiber from the machine when said feeding means are reversed, and means whereby the two feeding means will be rotated in opposite directions and means for reversing the feeding means.
- 10 41. A fiber cleaning machine comprising a primary feeding means, a cleaning drum adjacent thereto, a secondary feeding means, a cleaning drum therefor, means whereby when the primary feeding means is reversed the leaf to be cleaned will be delivered to the secondary feeding means, said secondary feeding means being arranged to discharge the cleaned fiber from the machine when said feeding means are reversed, means whereby the two feeding means will be rotated in opposite directions, means for reversing the feeding means, and means for rotating the secondary feeding means at a slower speed than the primary feeding means.
- 25 42. A fiber cleaning machine comprising two cleaning drums, means for rotating said drums, a feeding means for each drum, and means for rotating said feeding means at different speeds.
- 30 43. A fiber cleaning machine comprising two cleaning drums, means for rotating said drums in the same direction, a feeding means for each drum, means for operating said feeding means in opposite directions, one of said feeding means receiving the leaf to be cleaned from the other feeding means, and means for reversing the feeding means.
44. A fiber cleaning machine comprising two cleaning drums located close together one above the other, means for rotating said cleaning drums in the same direction, a feeding means for each drum arranged to feed downwardly to said drums, one of said feeding means being above the other, means for rotating said feeding means in opposite directions, means to reverse the direction of rotation of said feeding means, and means whereby the upper feeding means when reversed will deliver the leaf to be cleaned to the lower feeding means.
45. A fiber cleaning machine comprising two cleaning drums located close together one above the other, means for rotating said cleaning drums in the same direction, a feeding means for each drum arranged to feed downwardly to said drums, one of said feeding means being above the other, means for rotating said feeding means in opposite directions and at different speeds, means to reverse the direction of rotation of said feeding means, and means whereby the upper feeding means when reversed will deliver the leaf to be cleaned to the lower feeding means.

In testimony whereof I hereunto affix my signature in the presence of two witnesses this 17th day of November, 1905.

ANGEL PONS.
